UNITED STATES PATENT OFFICE.

CLAUDE REES AND CHARLES F. HINE, OF SAN FRANCISCO, CALIFORNIA.

DRYING APPARATUS.

Application filed October 22, 1924. Serial No. 745,147.

To all whom it may concern:

Be it known that we, CLAUDE REES and CHARLES F. HINE, citizens of the United States, and residents of the city and county 5 of San Francisco, State of California, have invented a certain new and useful Drying Apparatus, of which the following is a specification.

The invention relates to a drying apparatus for drying, dehydrating or partially dehydrating materials, such as fruit, vegetables or other products requiring drying to place them in condition for use or sale.

An object of the invention is to provide a 15 drying apparatus having a large drying capacity.

Another object of the invention is to provide a duplex drying apparatus in which two rows of tiers of the material to be dried 20 may be arranged.

Another object of the invention is to provide a drying apparatus provided with blowers for circulating air, the blowers being provided with means for reversing the 25 direction of the air circulation.

The invention possesses other advantageous features, some of which with the foregoing, will be set forth at length in the following description where we shall outline 30 in full that form of the apparatus of our invention which we have selected for illustration in the drawings accompanying and forming part of the present specification. In said drawings we have shown one form 35 of drying apparatus embodying our invention, but it is to be understood that we do not limit ourselves to such form, since the invention, as set forth in the claims, may be embodied in a plurality of forms.

40 Referring to said drawings:

Figure 1 is a horizontal section taken through a drying house embodying our invention, the section being taken on the line 1—1 Figure 4.

45 Figure 2 is a horizontal section taken through a drying house embodying our invention, the section being taken immediately below the ceiling on the line 2—2 Figure 4.

50 Figure 3 is in part an end elevation of a drying house embodying our invention.

Figure 4 is a vertical cross section through the drying house taken on the line 4—4 Figure 1.

Figure 5 is a side elevation, partly diagrammatic, of the means employed for controlling the discharge of air from the blower. 55

Figure 6 is a top or plan view of the blower housing and control devices shown in Figure 5.

Figure 7 is a side elevation of a truck 60 loaded with a tier of trays.

The drying apparatus of our invention comprises a house or other enclosing structure into which the material to be dried is introduced. The material is preferably ar- 65

ranged on trays and the trays arranged in tiers, the trays being constructed to permit the passage of air between the successive trays in the tier for the purpose of drying the material disposed on the trays. The 70 house is divided into two longitudinal drying chambers with an interposed heating chamber and the air for drying the material is circulated transversely in the house, passing through one drying chamber, thence 75 through the heating chamber and thence through the other drying chamber. The house is provided with a horizontal partition arranged over the drying chambers, forming a reverse air passage over the drying chambers and the means for circulating the air are arranged in the reverse air passage. 80

At opposite sides of the house, contiguous to the drying chambers, are longitudinally extending passages which open upward into the reverse air chamber, so that the air may circulate through the drying chambers and through the reverse air chambers. The house is also provided with a plurality of transverse partitions which prevent the free movement of the air longitudinally of the house, so that the air is circulated in the house in a more or less 85 helical path. Air is withdrawn at one end of the house by a blower and discharged 90 into the other end of the house and progresses in a more or less helical path through the house, the air being continuously circulated by blowers arranged in the reverse air chamber. 95

The drying apparatus of our invention 100 comprises a house having side walls 2—3 and end walls 4—5. The house is provided with a roof 6 and with a horizontal ceiling 7 disposed below the roof. Extending through the house are two parallel, spaced tracks 8

over which trucks 9 containing tiers 12 of trays containing the material to be dried, are moved. The trucks are entered into the house at one end thereof and gradually progress toward the other end, at which other end they are removed after the material has been suitably dried. The house is usually fully charged with trucks to its capacity and when a pair of trucks or a larger number of trucks are removed from one end of the house, the trucks within the house are advanced and a number of trucks equal to those removed, are introduced into the other end of the house. Doors are provided at the ends of the house for permitting the introduction and the removal of the trucks loaded with trays. The trays are provided with side walls which extend upward to a greater height than the end walls, so that when a tier of trays is formed, horizontal passages are provided, extending transversely through the tier, the side walls of the respective superposed trays are in contact, providing substantially continuous side walls for the tier and consequently the drying air is forced to pass transversely only through the tier. The side walls of the tier form partitions in the drying chambers, when the chambers are filled with tiers and these partitions are alined with partitions formed in the house to produce a plurality of successive transverse compartments, and means are provided in each compartment for transversely circulating the air therein.

Arranged between the two rows of tiers, carried by the two tracks, is a heating chamber in which suitable heaters 13 are arranged. These heaters preferably extend upward to adjacent the ceiling 7 so that the circulating air is brought into contact twice with the heaters during each circulation of the air. The heaters 13 preferably comprise tubular radiators, through which the gases of combustion from the furnace 14 pass.

The gases of combustion from the furnace enter a drum 15 arranged in a tunnel 16, disposed below the floor of the house, and from the drum 15 the gases pass upward through spaced conduits 17 into the lower headers 18 of the heaters. From the lower headers the gases pass upward through the tubes 19 into the upper header 21 and the upper headers of the heaters are connected to the stack 22 which extends upward above the roof of the house.

Disposed above the drying chambers and below the ceiling 7, is a substantially horizontal partition 23 which is of less width than the width of the house, which provides a reverse air passage 24 below the ceiling. Air circulated through the reverse air passage and through the drying and heating chambers and, since the heaters are arranged between the two drying chambers, the air is heated twice during each circulation and

is heated after it leaves one drying chamber and before it enters the other drying chamber. In the chamber below the horizontal partition 23, the air is heated by the lower portion of the heater 13 and in the reverse air chamber 24, the air is heated by the upper portion of the heater 13. Means are provided in the reverse air chamber for circulating the air transversely of the house.

Formed at the outside of each heating chamber, that is, between the heating chamber and the side wall of the house, is a longitudinal passage 26 extending from the floor to the ceiling 7, to permit the passage of air from the drying chamber to the reverse air chamber and vice versa. The longitudinal passages 26 serve as inspection passages, to permit inspection of the fruit being dried, and also serve to control the rate of progression of the air longitudinally through the house. The passageways 26 are provided at their ends with doors 27 to permit ingress and egress and are provided intermediate their ends with transverse partitions 28 which, when the tiers of trays are in place, are in alinement with the side walls of the alternate tiers, thus dividing the house into a plurality of compartments. The partitions 28 are provided with doors 29 to permit an observer to walk through the passage and the doors 29 also serve to control the rate of progression of the air through the house. The doors may be opened to any desired degree and when opened permit the movement of air from one compartment to the successive compartment and the degree of opening of the doors determines the rate at which the air moves longitudinally in the house from one compartment to the other.

The heating chamber, which is interposed between the two drying chambers, is provided with transverse partitions 31 which are alined at their ends with the partitions 28, so that they assist in dividing the house into a plurality of compartments. The partitions 31 and the partitions 28 are preferably provided at their edges with movable shutters 32 which may be moved into contact with the end walls of the tiers of trays, to prevent leakage of air through the space between the tiers and the partition walls.

The reverse air chamber is divided into a plurality of compartments by the vertically disposed partition walls 34 which are vertically alined with the partitions 28, so that the house, between the ceiling and the floor, is divided into a plurality of transverse compartments, through which air is circulated. The air is circulated through each compartment and a proportion of the air progresses from one compartment to the other, so that the air has a more or less helical path through the house. The partitions 34 are provided with doors to permit ac-

cess to the partitions and these doors 35 may be set in adjustable position to control the progression of air through the house.

The air in each compartment is preferably circulated by a blower arranged in the reverse air passage of the compartment and means are provided for reversing the direction of discharge of air from the blower, so that the direction of the circulating air may be reversed. Arranged in each compartment of the reverse air chamber is a blower housing 36 having air inlet chambers 37 arranged at opposite sides thereof. The housing is preferably of the same height as the reverse air chamber and the space between the housing and the transverse walls is closed by partitions 38 so that all air must pass through the blower housing. The plurality of blowers are arranged in alinement and are driven by the shaft 39 which is driven by the motor 41. The blowers are preferably driven continuously in one direction and air control means are provided for reversing the direction of the flow of air in the compartments. Each blower housing 36 is provided on opposite sides with discharge openings which are controlled by the gates or valves 42-43, the two gates lying on opposite sides of the partition 38. Similarly, each inlet housing 37 is provided with two gates or valves 45-46, disposed on opposite sides of the partition wall 38. The various valves are preferably interconnected, so that valves 42 and 46 move together and valves 43 and 45 move together, these valves being disposed on opposite sides of the casing. When valves 42 and 46 are closed, valves 43 and 45 are opened and vice versa. With the valves in the position shown in Figures 5 and 6, valves 46 and 42 being closed and valves 45 and 43 being opened, the air enters the inlet casing 37 through the openings controlled by the valve 45 and discharges through the opening controlled by the valve 43. This causes a movement of the air in the direction indicated by the full arrows, that is, from left to right. With the position of the valves reversed, the air travels in the direction indicated by the broken arrows, that is, from right to left. Means are provided for connecting the valves 45 and 46 together in pairs, so that as one valve is closed the other is opened, and also for connecting the valves 43 and 42 together so that these valves also move simultaneously in opposite directions. The valves 45 and 46 are connected together by the link 47 so that they move simultaneously, and the valves 45 and 42 are secured to the same shaft 48 and the valves 43 and 46 are secured to the same shaft 49, so that all of the valves are simultaneously moved. The valves are moved by chains 51-52, the chain 51 being connected to the valves 45 and the chain 52 being connected to the

valve 42. These chains pass over sprockets 53-54, mounted on the shaft 55, which is rotated by the hand wheel 56 through suitable mechanical connections such as the pulleys 57-58 and the belt 59. Rotation of the hand wheel 56 causes a movement of all of the valves to open the inlet on one side of the partition and the outlet on the opposite side of the partition, so that the air may be circulated in either direction through the drying chamber. In order that the fruit on the trays may be dried equally at opposite ends of the trays in the tiers, it is advisable to reverse the direction of flow of the air at certain intervals, so that all of the fruit will be equally dried.

Means are provided for causing a progression of air through the house, this means preferably comprising a blower 61 driven by the motor 62 and having its intake conduit 63 opening into the house adjacent one end thereof, preferably that end into which the green fruit is introduced. The blower 61 is provided with a discharge conduit 64 which opens into the tunnel 16 arranged below the floor of the house, and with an auxiliary discharge conduit 65 for discharging a portion of the air to the atmosphere. The tunnel 16 extends for substantially the full length of the house and the air passing through the tunnel contacts with the hot drum 15 which extends for the length of the heaters, and in passing in contact with the drum, the air is heated. The tunnel opens up through the floor of the house at the opposite end of the house from the blower 63 and opens into the first compartment in the house. The heated air is circulated in this compartment by the blower arranged therein and passes horizontally through the passages in the tiers of trays arranged in the drying chambers. The air gradually passes downward through the house into the successive compartments and in the successive compartments is reheated twice during each circulation of the air, due to the arrangement of the heater in both the upper and lower chambers in the house. In passing through the house and in contact with the fruit to be dried, the warm air takes up moisture and this moisture laden air is recirculated through the house by the blower 61, so that hot dry air is not brought into contact with the fruit. The air passing through the house is gradually renewed to replace the air which discharges through the conduit 65 and the moisture removed from the fruit discharges with the air through the conduit 65, the recirculated air being also moist so that the desired condition of humidity is maintained in the house at all times. By virtue of this arrangement, we have provided a drying apparatus capable of treating two rows of tiers of fruit at the same time. By providing a central heating chamber, the efficiency

of the equipment is increased, since there is less dissipation of heat to the atmosphere.

We claim:

1. A drying apparatus comprising a house, two parallel tracks arranged in the house and adapted to receive trucks loaded with tiers of trays containing the material to be dried, a horizontal partition dividing the house into upper and lower chambers, a heater arranged in the house between the two tracks and disposed in both chambers, means for circulating air through the two chambers serially.
2. A drying apparatus comprising a house, two parallel tracks arranged in the house and adapted to receive trucks loaded with tiers of trays containing the material to be dried, a horizontal partition dividing the house into upper and lower chambers, a heater arranged in the house between the two tracks and disposed in both chambers, means for circulating air through the two chambers serially and means for reversing the direction of the flow of air.
3. A drying apparatus comprising a house, two parallel tracks arranged in the house and adapted to receive trucks loaded with tiers of trays containing the material to be dried, a horizontal partition dividing the house into upper and lower chambers, a heater arranged in the house between the two tracks and disposed in both chambers, means for circulating air through the two chambers serially and means for causing a progression of the circulating air through the house.
4. A drying apparatus comprising a house, two parallel tracks arranged in the house and adapted to receive trucks loaded with tiers of trays containing the material to be dried, a horizontal partition dividing the house into upper and lower chambers, a heater arranged in the house between the two tracks and disposed in both chambers, means for circulating air through the two chambers serially, means for causing a progression of the circulating air through the house and means for controlling the rate of progression of the air.
5. A drying apparatus comprising a house, two parallel tracks arranged in the house and adapted to receive trucks loaded with tiers of trays containing the material to be dried, a horizontal partition dividing the house into upper and lower chambers, a heater arranged in the house between the two tracks and disposed in both chambers, means for circulating air through the two chambers serially and a blower having its inlet opening into one end of the house and its discharge opening into the other end of the house.
6. A drying apparatus comprising a house, two parallel tracks arranged in the house and adapted to receive trucks loaded with tiers of trays containing the material to be dried, a horizontal partition dividing the house into upper and lower chambers, a heater arranged in the house between the two tracks and disposed in both chambers, means for circulating air through the two chambers serially, a blower having its inlet opening into one end of the house, a discharge conduit for the blower opening into the other end of the house, and a second blower discharge conduit opening to the atmosphere.
7. A drying apparatus comprising a house, two parallel tracks arranged in the house and adapted to receive trucks loaded with tiers of trays containing the material to be dried, the trays being formed to permit the passage of air through the tiers in a transverse direction only, a horizontal partition dividing the house into upper and lower chambers, a heater arranged in the house between the two tracks and disposed in both chambers, transverse partitions in the upper chamber dividing the chamber into a plurality of compartments and means in the compartments for circulating air through the chambers serially.
8. A drying apparatus comprising a house, two parallel tracks arranged in the house and adapted to receive trucks loaded with tiers of trays containing the material to be dried, the trays being formed to permit the passage of air through the tiers in a transverse direction only, a horizontal partition dividing the house into upper and lower chambers, a heater arranged in the house between the two tracks and disposed in both chambers, transverse partitions in the upper chamber dividing the chamber into a plurality of compartments, means in the compartments for circulating air through the chambers serially and means for reversing the direction of circulation of the air.
9. A drying apparatus comprising a house, two parallel tracks arranged in the house and adapted to receive trucks loaded with tiers of trays containing the material to be dried, the trays being formed to permit the passage of air through the tiers in a transverse direction only, a horizontal partition dividing the house into upper and lower chambers, a heater arranged in the house between the two tracks and disposed in both chambers, transverse partitions in the upper chamber dividing the chamber into a plurality of compartments, means in the compartments for circulating air through the chambers serially and means for causing a progression of the circulating air through the house.
10. A drying apparatus comprising a house, two parallel tracks arranged in the house and adapted to receive trucks loaded with tiers of trays containing the material to be dried, the trays being formed to permit the passage of air through the tiers in a transverse direction only, a horizontal par-

tion dividing the house into upper and lower chambers, a heater arranged in the house between the two tracks and disposed in both chambers, transverse partitions in the upper chamber dividing the chamber into a plurality of compartments, means in the compartments for circulating air through the chambers serially, means for causing a progression of the circulating air through the house and means for controlling the rate of progression of the air.

11. A drying apparatus comprising a house, two parallel tracks arranged in the house and adapted to receive trucks loaded with tiers of trays containing the material to be dried, the trays being formed to permit the passage of air through the tiers in a transverse direction only, a horizontal partition dividing the house into upper and lower chambers, a heater arranged in the house between the two tracks and disposed in both chambers, transverse partitions in the upper chamber dividing the chamber into a plurality of compartments, blowers in the compartments for circulating air through the chambers serially, means controlling the air inlet to the blowers, means controlling the air discharge from the blowers and means for actuating the controlling means to reverse the direction of circulation of the air.

12. A drying apparatus comprising a house, heaters arranged in the center of the house, drying chambers at opposite sides of the heaters, a horizontal partition overlying the drying chambers and forming a reverse air space connecting the two drying chambers, tiers of trays containing the material to be dried arranged in the drying chambers, said tiers being formed to permit the passage of air therethrough transversely only and means for circulating air through said drying chambers serially.

13. A drying apparatus comprising a house, heaters arranged in the center of the house, drying chambers at opposite sides of the heaters, a horizontal partition overlying the drying chambers and forming a reverse air space connecting the two drying chambers, tiers of trays containing the material to be dried arranged in the drying chambers, said tiers being formed to permit the passage of air therethrough transversely only, means for circulating air through one drying chamber, a heater, the other drying chamber and the reverse air passage serially and means for reversing the direction of circulation of the air.

14. A drying apparatus comprising a house, heaters arranged in the center of the house, drying chambers at opposite sides of the heaters, longitudinal passageways along the remote sides of the drying chambers, a horizontal partition overlying the drying chambers and forming a reverse air space

connecting the two passageways, said heaters extending upward into the reverse air space, vertical transverse partitions in said reverse air space to prevent longitudinal movement of the air in the reverse air space and means in said space for causing movement of air through the drying chambers and reverse air space serially.

15. A drying apparatus comprising a house, heaters arranged in the center of the house, drying chambers at opposite sides of the heaters, tracks extending through the drying chambers adapted to carry trucks carrying tiers of trays containing the material to be dried, the tiers being closed at their sides and open at their ends to permit the passage of air therethrough in a transverse direction only, longitudinal passageways along the remote sides of the drying chambers, partitions in said passageways arranged to occur in alinement with the closed sides of the tiers, a horizontal partition overlying the drying chambers and forming a reverse air passage connecting the two passageways, said heaters extending upwardly into said reverse air passage, vertical partitions in said reverse air passage alined with the partitions in said longitudinal passageways and means in the reverse air passage for circulating air through the reverse air passage and the drying chambers and the heaters.

16. A drying apparatus comprising a house, heaters arranged in the center of the house, drying chambers at opposite sides of the heaters, tracks extending through the drying chambers adapted to carry trucks carrying tiers of trays containing the material to be dried, the tiers being closed at their sides and open at their ends to permit the passage of air therethrough in a transverse direction only, longitudinal passageways along the remote sides of the drying chambers, partitions in said passageways arranged to occur in alinement with the closed sides of the tiers, a horizontal partition overlying the drying chambers and forming a reverse air passage connecting the two passageways, said heaters extending upwardly into said reverse air passage, vertical partitions in said reverse air passage alined with the partitions in said longitudinal passageways, blowers in the reverse air passage for circulating air through the reverse air passage and drying chambers and the heaters and a blower for causing a progression of air through the house.

17. A drying apparatus comprising a house, heaters arranged in the center of the house, drying chambers at opposite sides of the heaters, tracks extending through the drying chambers adapted to carry trucks carrying tiers of trays containing the material to be dried, the tiers being closed at their sides and open at their ends to permit the passage of air therethrough in a trans-

verse direction only, longitudinal passageways along the remote sides of the drying chambers, partitions in said passageways arranged to occur in alinement with the closed 5 sides of the tiers, a horizontal partition overlying the drying chambers and forming a reverse air passage connecting the two passageways, said heaters extending upwardly into said reverse air passage, vertical partitions in said reverse air passage alined with the partitions in said longitudinal passageways, blowers in the reverse air passage for circulating air through the reverse air 10 passage and drying chambers and the heaters and a blower connected at its intake side to one end of the house and at its discharge 15 side to the other end of the house.

18. A drying apparatus comprising a house, heaters arranged in the center of the 20 house, drying chambers at opposite sides of the heaters, tracks extending through the drying chambers adapted to carry trucks carrying tiers of trays containing the material to be dried, the tiers being closed at 25 their sides and open at their ends to permit

the passage of air therethrough in a transverse direction only, longitudinal passageways along the remote sides of the drying chambers, partitions in said passageways arranged to occur in alinement with the closed 30 sides of the tiers, a horizontal partition overlying the drying chambers and forming a reverse air passage connecting the two passageways, said heaters extending upwardly into said reverse air passage, vertical 35 partitions in said reverse air passage alined with the partitions in said longitudinal passageways, blowers in the reverse air passage for circulating air through the reverse air passage and drying chambers and the heaters, a blower connected at its intake side to one end of the house, a conduit connecting the discharge side of the blower with the other end of the house and means in said conduit for heating the air passing there- 40 through.

In testimony whereof, we have hereunto set our hands.

CLAUDE REES
CHARLES F. HINE.
